WRITING INSTRUMENT DESK SET BASE

Donald W. Doman, Janesville, Wis., assignor to The Parker Pen Company, Janesville, Wis., a corporation of Wisconsin

Filed Sept. 20, 1957, Ser. No. 47,786

Term of patent 14 years

(Cl. D74—1)

FIG. 1

FIG. 2

FIG. 4

FIG. 1 is a perspective view of a writing instrument desk set base, showing my new design;

FIG. 2 is a top plan view thereof;

FIG. 3 is a side elevational view thereof; and

FIG. 4 is an end elevational view thereof;

I claim:

The ornamental design for a writing instrument desk set base, substantially as shown.
